UNITED STATES PATENT OFFICE.

FREDERIC T. DE LONG, OF CHICAGO, ILLINOIS, ASSIGNOR TO CHICAGO RAILWAY EQUIPMENT COMPANY, OF CHICAGO, ILLINOIS, A CORPORATION OF ILLINOIS.

BRAKE-BEAM STRUCTURE.

Application filed May 4, 1927. Serial No. 188,682.

My invention relates to railway rolling stock and consists in an improved brake beam strut and third or fourth point support chair. It is customary to use a rotatable 5 strut in a truss brake beam so that the angle of inclination of the brake lever may be changed without using a new strut or a new brake beam. It is also customary to mount a third point support chair on the strut. It is 10 clear that the relation between the chair and the strut must be changed if the strut is reversed since the position of the chair relative to its support should not be changed.

The main object of my invention is to provide 15 a strut and chair structure which will permit the reversal of the strut without changing or removing the chair from the strut. In the accompanying drawings which illustrate my invention

20 Figure 1 is a transverse section through a brake beam illustrating in elevation my improved strut and chair and indicating a third point support for the chair.

Figure 2 is a view of the end of the strut 25 and of the side of the chair.

Figures 3 and 4 correspond to Figures 1 and 2 but illustrate a modified form of my invention.

Figure 5 is a section on line 5—5 of Figure 30 3.

Figures 6 and 7 are similar to Figures 1 and 2 but illustrate another modification of my invention.

Figures 8 and 9 similarly illustrate another 35 modification of my invention.

In the structure illustrated in Figures 1 and 2, the strut is shown as engaging the compression member 2 and the tension member 3 of a brake beam. The right hand end 40 of the strut forms a bracket 4 of a well-known type which permits the strut to be reversed so as to accommodate a brake lever inclined in the opposite direction to the inclination provided by the strut in the position illustrated. On the outer end of bracket 4 is a journal 5 projecting axially of the strut and mounting a chair 6 which rides on a track member 7 such as is ordinarily provided under brake beams.

50 Preferably the journal bearing in chair 6 will be convexed as indicated at 8 to permit the chair to tilt lengthwise of the strut as well as transversely of the strut so as to accommodate any inclination which may be provided in a track 7. Washer *w* and cotter *c* hold

the chair in assembled position with the strut. The base of the chair has depending flanges 6^a which extend on each side of the track 7 to prevent accidental turning over of the chair. These flanges 6^a can be eliminated if 60 desired.

In the modification illustrated in Figures 3, 4 and 5 the outer end of the strut has an extension 9 which mounts a sleeve 10 which is provided with parallel ears 11 between 65 which the chair 12 is carried in the manner usually provided by the end of the strut proper. Sleeve 10 is retained on the strut extension by a cotter 13, the opening in the sleeve being elongated circumferentially of 70 the sleeve to permit the sleeve to rotate relative to the strut, when the latter is reversed, so that the chair may remain in the vertical position in which it will properly engage its track 14.

In the modification illustrated in Figures 6 and 7, the strut extension forms spaced ears 15 and 16 disposed at an angle to the vertical corresponding to the inclination of the brake lever. The chair 17 has an upwardly extending hub 18 similarly inclined from the vertical. When the strut is reversed the chair is removed from the strut and is reversed so that its ear or hub 18 extends diagonally upward from the right to the left and the relation 85 between its bearing surface and track 19 is unchanged.

In the construction shown in Figures 8 and 9, the extension 20 on the strut is rectangular in cross section and the chair 21 is provided 90 with two legs 22 and 23, either one of which is adapted to engage the track member 24.

In each form of my invention, the strut may be formed of one piece and in all of the forms except that shown in Figures 6 and 7 reversal 95 of the strut does not require disassembly of the chair as the latter will automatically maintain its proper position. In the form shown in Figures 1 and 2, the center of gravity of the chair below its journal will cause it to automatically swing to the vertical position indicated. In the forms illustrated in Figures 6 to 9, the chair will be positively held in the proper vertical position. Obviously many other modifications in the detailed structure of my invention may be made without departing from the spirit thereof and I contemplate the exclusive use of such variations as fall within the scope of my 100 claims.

I claim:

1. In a brake beam, a third or fourth point support chair angularly adjustable on the beam in a vertical plane extending lengthwise of the beam.
2. In a brake beam, a reversible strut and a third point support chair mounted on said strut independently of the beam and angularly adjustable about the axis thereof.
3. In a brake beam, a compression member, a tension member, a reversible strut between said members with a rigid portion extending beyond one of them, and a third point support chair mounted on said portion and angularly adjustable about the axis thereof.
4. In a brake beam, a one piece reversible strut, and a third point support chair on said strut and adjustable angularly of the strut axis.
5. In a brake beam, a one-piece reversible strut, and a third point support chair mounted on said strut to pivot about the strut axis.
6. In a brake beam, a reversible one piece strut, and a third point support chair mounted on said strut and adapted to automatically position itself to engage a support arm irrespective of the inclination of said strut about its axis or of the longitudinal inclination of the beam.
7. In a brake beam, a reversible strut, and a third point support chair pivotally mounted on said strut to freely rotate in a plane extending transversely of the strut axis, said chair having its center of gravity below the axis of its pivot.
8. In a brake beam, a compression member, a tension member, a reversible strut between said members and extending beyond one of them, and a third point support chair pivotally mounted on the projecting portion of said chair to permit reversal of said strut without affecting engagement of said chair with its support.
9. In a brake beam, a compression member, a tension member, a reversible strut between said members terminating in an axial journal projecting beyond one of said members, and a third point support chair having a bearing for said journal which bearing is convex lengthwise of the journal to permit tilting of said chair on said journal axially thereof.
10. In a brake beam, a third or fourth point support chair mounted on the beam to swing freely in a plane extending lengthwise of the beam.
11. In a brake beam, a third or fourth point support chair mounted on the beam to swing freely in any direction relative to the beam.
12. In a brake beam, a strut, and a third point support chair mounted on said strut so as to swing in any direction relative to the strut.
13. In a third or fourth point support chair for brake beams, a base for sliding in one direction on a support, elements for engaging a chair mounting so as to permit the chair to pivot transversely of said direction, and depending flanges on the chair for engaging the sides of a track member to prevent accidental pivoting of said chair transversely of said direction.
14. In a third or fourth point support chair for a brake beam, a base adapted to facilitate sliding of the chair on a support in a direction extending transversely of the length of the beam, and elements for engaging a chair mounting so as to permit the chair to pivot in a vertical plane extending lengthwise of the beam.
15. In a third or fourth point support chair for a brake beam, a base adapted to facilitate sliding of the chair on a support in a direction extending transversely of the length of the beam, elements for engaging a chair mounting so as to permit the chair to pivot in a vertical plane extending lengthwise of the beam and elements to prevent accidental pivoting of said chair on its mounting.

In testimony whereof I hereunto affix my signature this 26th day of April, 1927.

FREDERIC T. DE LONG.
